CLAIM

The ornamental design for a medical apparatus for odor dispensing as shown and described.

DESCRIPTION

1. Medical apparatus for odor dispensing

1.1 : Perspective

1.2 : Top

1.3 : Left

1.4 : Front

1.5 : Right

1.6 : Back

1.7 : Bottom

(Continued)

The broken lines shown in the figures are for the purpose of illustrating portions of the medical apparatus for odor dispensing and form no part of the claimed design.

1 Claim, 7 Drawing Sheets
